UNITED STATES PATENT OFFICE.

JAMES WILLIAM DECKERT, OF OAKVILLE, CANADA.

HIDE-WORKING MACHINERY.

SPECIFICATION forming part of Letters Patent No. 791,015, dated May 30, 1905.

Application filed July 21, 1904. Serial No. 217,455.

To all whom it may concern:

Be it known that I, JAMES WILLIAM DECKERT, leather-splitter, a citizen of the United States of America, residing in the town of 5 Oakville, county of Halton, Province of Ontario, Canada, have invented certain new and useful Improvements in Hide-Working Machinery, of which the following is a specification.

10 My invention relates to improvements in hide-working machinery; and one object of my invention is to design a machine that can be used by changing certain parts for unhairing, unfleshing, and stoning hides.

15 Another object is to construct my machine so that it will adjust itself to the different thicknesses of the hide, so that same will be thoroughly prepared for leather.

Another object is to regulate the pressure 20 of the hide against the cylinder.

A still further object in my preferred form of invention is to horizontally support the hide and first move it with the rotation of the cylinder and then to return it against the rotation of same, thus insuring the most effective 25 work being done thereon; and it broadly consists of a rotary cylinder, means underneath same adjustable to the different thicknesses 30 of the hide placed between same and said cylinder, so that thin as well as thick portions thereof will be thoroughly prepared for leather, and a flexible bolster underneath said cylinder and upon said means for supporting the hide, the flexible bolster being movable 35 in a straight or curved line transversely to the axis of the fixed rotary cylinder and the said adjustable means.

My invention further consists in its preferred form in providing a particular carriage 40 for the bolster and in providing means for reversing same and other combination of elements, as hereinafter more particularly explained.

My machine as illustrated is equipped for 45 unhairing hides, and I shall describe its principle in performing that function. Of course it will be understood that by changing the knives or stones in the cylinder the machine will perform the different classes of work before enumerated.

Figure 1 is a front side elevation of my ma-

chine, parts being broken away and parts in section. Fig. 2 is a longitudinal vertical section on the line *c d*, Fig. 1, showing a hide clamped in position. Fig. 3 is an enlarged 55 perspective view of the under side of the preferred form of carriage for the bolster. Fig. 4 is an enlarged vertical section on the line *a b*, Fig. 1; and Fig. 5 is a detail view, partly 60 in section, of the preferred form of sectional ring-roller.

In the drawings like characters of reference indicate corresponding parts in each figure.

A is the bed of the machine, and *C* and *C'* the head-blocks suitably secured thereto. 65 Suitably mounted in these head-blocks is the cylinder *D*. On one end of the shaft *E* of the cylinder is the drive-pulley *F*, which is always driven in one direction.

G, the roller, made of resilient material, is 70 suitably mounted in the head-blocks underneath the cylinder, and each end of the shaft *H* of same is provided with pinions *I* and *I'*, which mesh, respectively, with the gear-wheels *J* and *K*, keyed to the main shaft *L*, 75 held in suitable bearings in the said head-blocks.

M and *N* are the front and rear brackets, suitably supported to the bed *A* and upon which are respectively secured the plates *P* 80 and *O*. These two plates, together with the cylinder *D* and the roller *G*, form what I call a "ring-chamber" *Q*. In this ring-chamber and resting upon the roller *G* is a sectional ring-roller *R*. By means of the plates *P* and 85 *O* it will be understood that the axis of the sectional ring-roller will always be parallel with the axes of the roller *G* and the cylinder *D*.

S represents suitable extensions of the machine-frame and are designed to support 90 the carriage *T*, to which is suitably secured the bolster *U*. The cylinder *D* is revolved quite rapidly and always in the same direction, as shown by arrow, and the roller *G* is revolved at a very much lower rate of speed, and 95 consequently the sectional ring-roller *R* revolves slowly. The sectional ring-roller is revolved by means of the roller *G*, bolster *U*, and cylinder *D*. Part of the hide is placed on the bolster in the position shown with the hair uppermost, and by means of any suitable clamp *V*, suitably hinged to the carriage, as 100

at v , same is secured to said bolster. As the gear-wheels J and K mesh with the racks j and k of the carriage T , it will be understood that the said carriage will be moved in the direction indicated by arrow and the hide moved between the cylinder D and the sectional ring-roller R . Although I may use any construction of cylinder in connection with my hide-working machine, I preferably use the cylinder described and claimed in my application, Serial No. 212,672, filed June 15, 1904. For unhairing purposes the blades m and n are made of rawhide. By means hereinafter described when the carriage T is moved to the limit of its inward movement the gearing is reversed and the carriage is returned to normal position, which is shown in Fig. 2, and this operation is repeated. As the cylinder is always rotated in the same direction, it will be seen that I first move the hide with the rotation of the cylinder and then return it against the rotation of same, thus insuring the most effective work being done thereon. If necessary, the described operation may be repeated several times. When the portion of the hide worked upon has been unhaired, the clamp V is thrown up into the position shown in Fig. 1 and the part of the hide held in the hide-box W placed and clamped in position and unhaired. Some of the most essential parts of my present machine are embodied in my application for improvements in machines for stoning leather, Serial No. 208,906, filed May 20, 1904. In this application the broad claims cover the combination of the stoning-cylinder with a sectional ring-roller operating thereunder upon a roller made of resilient material, the said ring-roller being used for the same purpose as the one employed in the present machine. In this said application I also claim means for keeping the ring-roller parallel with the stoning-cylinder. I also claim the cam-pillars for regulating the pressure of the ring-roller against the hide through the roller made of resilient material. The said sectional ring-roller is firmly yet yieldingly held by the roller G against the bolster and is constructed so as to keep all parts of the hide close in contact with said cylinder, as was described in the said application. As it is necessary to show fully the points of merit in the present machine, I shall describe the operation of its sectional ring-roller. The preferred form of the sectional ring-roller is made of a plurality of rings t , provided with a central hole t' , through which passes the spindle t'' . As will be seen from Fig. 5, the rings t abut against each other and by reason of this and the collar t^3 , keyed on the said spindle, are held from longitudinal movement. t' represents the end collars removably secured to said spindle and capable of being adjusted in order to regulate the closeness of the operation of the rings to each other. The said rings are preferably

provided with flanges t^5 , which overhang the collars t^3 . Sufficient space is left between the collars t^3 and the inner side of the flanges t^5 so as not to interfere with the movement of the rings. By the construction just described it will be understood that when a hide is being prepared if a thick portion thereof should pass between the cylinder D and, for instance, the rings t^6 the said rings will be moved down, as shown in Fig. 5, and thus be more deeply depressed into the roller G , so as to permit of the passage of a thick portion of the hide; but yet by reason of the rubber cushion afforded by said roller the said rings will keep the hide in close contact with the cylinder. In case a thin piece of hide should be passing between any of the rings and the cylinder, from the operation just described it will be understood that that portion of the roller G underneath the rings between which and the cylinder the thin portion of the hide is passing will move said rings upwardly, so as to keep the thin portion of the hide in close contact with the cylinder. It will of course be understood that the bolster U is made of suitable flexible material that will permit of the operation just described. From the operation and construction just described it will be understood that my machine will adjust itself to different thicknesses of the hide, so that it will be thoroughly unhaired. A' represents plates suitably secured to the plates P and O for the purpose of preventing the sectional ring-roller R from moving out of the ring-chamber Q . In the construction shown the said plates are supported in position by means of tapered centrally-slotted blocks B' , resting upon the plates P and O and underneath their lower ends and down through which pass the screws B^2 into the plates O and P . B^3 represents screws which secure the free ends of said plates to the plates P and O . By means of the slotted blocks B' and the slots b and b' in the plates A' it will be understood that these said plates may be moved to or from said sectional ring-roller. In place of this construction I may make the brackets M and N adjustable, as described in my before-mentioned application. In order to prevent the bolster from coming in contact with parts of the machine other than the sectional ring-roller and, further, in order to maintain its tautness, I provide suitable rollers C^2 , which may be held in bearings in any suitable manner in the machine-frame. In the construction shown (see Fig. 1) the said rollers are journaled at their inner ends in the front bracket M' and at their outer ends in the head-blocks, as shown at c .

In order that the carriage T may always travel in a straight line, I provide same with grooves D' , in which fit correspondingly-shaped rails D^2 , secured to or forming part of the extensions S .

One end of the bolster U is secured to the

cross-bar v' of the carriage T, and the other end of said bolster is secured to the movable cross-bar v^2 of said carriage. The ends v^4 of the adjustable cross-bar v^3 operate in the slots v^5 of the carriage. By means of the bolts v^6 connecting the adjustable cross-bar v^3 with the fixed cross-bar v^7 and the nuts v^8 on said bolts it will be understood that said adjustable cross-bar is moved in said slots, and thus the tautness of the bolster U is adjusted. Between the cross-bar v' and the cross-bar v^2 is a space in which fits the head v^9 of the clamp V. From Fig. 2 it will be seen that the said head of said clamp holds the hide in position. I of course do not confine myself to the construction of the carriage shown and described.

D¹² represents water-pipes through which water passes in order to keep the working parts of the machine free from hair, &c.

It is necessary that the sectional ring-roller R be held at all points against the cylinder, and for that purpose I use any suitable means, preferably those described in my application Serial No. 208,906. Briefly stated, the shaft H has bearing in the sleeves O², in turn held in the bearing-blocks O³, which have movement in the slots O⁴, formed in the head-blocks. Secured to or forming part of the sleeves O² are threaded shanks O⁵.

O⁶ represents the top members of the cam-pillars, and O⁷ the lower members of same, which are suitably secured to the bed A. As shown, both members of the cam-pillars are provided with a common core O⁸, in which is held the connecting-pin O⁹, around which the top member O⁶ turns. As will be seen from Figs. 1 and 2, the threaded shank O⁵ rests in the upper part of the core O⁸. As will be seen from the drawings, the lower end of the top members O⁶ are constructed with a cam-surface O¹⁰, which coacts with a similar cam-surface O¹¹, constructed in the top of the members O⁷. By means of a rod O¹², suitably attached to the levers O¹³ of the top members O⁶, the said levers are moved so as to raise or lower said top members, and thus regulate the pressure of the roller G against the sectional king-roller. By means of any suitable arm O¹⁴ the rod O¹² is operated.

When the roller G is quite long, I prefer to use a king-roller G' and give same bearings in the cam-pillars before described, as clearly set forth in my application Serial No. 208,906. As shown in Figs. 1 and 2, I preferably operate the roller G from the gear-wheel K, so that the direction of rotation of said roller will be changed when the carriage T is reversed.

F' is any suitable support in which is held a rod F², held in the position shown in Figs. 1 and 4 by means of the spring F³, held within said support.

F⁴ is a pivoted arm, the upper end F⁵ of which is in the path of movement of a number of pegs suitably held in the carriage T.

In the position shown in Figs. 1 and 2 the direction of movement of the carriage T is just reversed. As the adjustable cross-bar v^3 of said carriage moves close to the head-blocks a pin abuts against the top end F⁶ of the pivoted arm F⁴ and moves the beveled portion F⁷ thereof from the left-hand side of a beveled head F⁸ of the rod F² to the right-hand side of same, as shown in Fig. 4. As the said pivoted arm is keyed to the shaft F⁹, held in suitable bearings, the movement of said shaft moves the arm F⁴, keyed thereto, so as to operate any well-known friction-clutches F¹⁰ to throw the beveled pinion F¹¹ in gear with the drive-shaft F¹² of the drive-pulley F¹³, thus operating the beveled pinion F¹⁴, held in any suitable bearing F¹⁵ by its shaft F¹⁶, in the direction indicated by arrow. Keyed on the end of this shaft is a gear-wheel F¹⁷, which meshes with the pinion F¹⁸ on the end of the main shaft L and through same, and the parts before described reverse the said carriage. As soon as the cross-piece v' moves close to the head-blocks the pin F⁶ (shown in Fig. 1) abuts against the pivoted arm F⁴, moving same to the left-hand side of the beveled head F⁸ of the rod F², thus operating the shaft F⁹, thus unclutching the beveled pinion F¹¹ from the shaft F¹² and throwing the beveled pinion F¹⁴ in clutch with said shaft, thus reversing the train of gear and said carriage.

It will of course be understood that I do not confine myself to the means shown and described for reversing the machine, nor to the means for transmitting energy to the roller G and carriage T.

By means of the hand-wheels E² it will be understood that the shaft E of the cylinder D may be raised or lowered, as was fully described in my application Serial No. 208,906.

By means of the handle G³ of the pivoted arm F⁴ it will be understood that the operator may reverse the direction of movement of the bolster at will.

It will of course be understood that the essential elements of my machine can be employed to advantage in machines differing in other respects from that herein shown and described for performing the various operations upon hides, and it must be understood that I do not, broadly, limit myself to their use in connection with any particular construction or arrangement of other parts.

As will be noticed from the drawings, I preferably place the rollers G and R and cylinder D so that their axes will be in a vertical line.

I do not confine myself to the construction herein shown and described, as same can be altered in many ways without departing from the spirit of my invention.

What I claim as my invention is—

1. In a machine of the class described, the combination with a rotary cylinder, and means for rotating same always in one direction, of a roller, underneath said cylinder and parallel

- thereto, constructed of a plurality of sections having independent movement of each other and in conformity with the thickness of the work under manufacture, so that all parts of the work under manufacture may be constantly kept in contact with the cylinder; a flexible bolster stretched underneath said cylinder and upon the plurality of sections of said roller, and means for moving said flexible bolster back and forth underneath said cylinder so that as the cylinder always revolves in one direction it will do work in the direction of its rotation when the bolster is moved back, and do work against the direction of its rotation when the bolster is moved forth.
2. In a machine of the class described, the combination with a rotary cylinder, and means for rotating same always in one direction, of a flexible bolster stretched underneath said cylinder; a roller, underneath said cylinder and parallel thereto, constructed of a plurality of sections having independent movement of each other and in conformity with the thickness of the work under manufacture, so that all parts of the work under manufacture may be constantly kept in contact with the cylinder; a roller made of resilient material for firmly yet yieldingly holding the sections of said roller in place, and means for moving said flexible bolster back and forth underneath said cylinder so that as the cylinder always revolves in one direction it will do work in the direction of its rotation when the bolster is moved back, and do work against the direction of its rotation when the bolster is moved forth.
3. In a machine of the class described, the combination with a stationarily-mounted rotary cylinder, and means for operating same, of a flexible bolster horizontally stretched underneath said cylinder; means for moving same back and forth; a ring-roller composed of a plurality of rings resting against the under side of said bolster, and a rubber roller upon which said ring-roller rests.
4. In a machine of the class described, the combination with a machine-frame; a rotary cylinder stationarily mounted in said frame, and means for operating same, of a flexible bolster horizontally stretched underneath said cylinder; a movable carriage on which said bolster is stretched; means for operating said carriage back and forth; a ring-roller composed of a plurality of rings resting against the under side of said bolster, and a roller made of resilient material and upon which said ring-roller rests.
5. In a machine of the class described, the combination with a machine-frame; a rotary cylinder stationarily mounted in said frame, and means for operating same, of a flexible bolster horizontally stretched underneath said cylinder; a movable carriage on which said bolster is stretched; means for operating said

carriage back and forth; a ring-roller composed of a plurality of rings resting against the under side of said bolster; a roller made of resilient material and upon which said ring-roller rests, and adjustable bearings for said roller so as to raise or lower said sectional ring-roller.

6. In a machine of the class described, the combination with a machine-frame; a rotary cylinder stationarily mounted in said frame, and means for operating same, of a flexible bolster horizontally stretched underneath said cylinder; a movable carriage on which said bolster is stretched; means for operating said carriage back and forth; a ring-roller composed of a plurality of rings resting against the under side of said bolster; a roller made of resilient material and upon which said ring-roller rests; adjustable bearings for said roller so as to raise or lower said sectional ring-roller, and two plates suitably supported in said machine-frame and on each side of said sectional ring-roller.

7. In a machine of the class described, the combination with a machine-frame; a rotary cylinder stationarily mounted in said frame, and means for operating same, of a flexible bolster horizontally stretched underneath said cylinder; a movable carriage on which said bolster is stretched; means for operating said carriage back and forth; a ring-roller composed of a plurality of rings resting against the under side of said bolster; a roller made of resilient material and upon which said ring-roller rests; adjustable bearings for said roller so as to raise or lower said sectional ring-roller; two plates suitably supported in said machine-frame and on each side of said sectional ring-roller, and two retaining-plates suitably secured on the upper side of said first-mentioned plates and on each side of said sectional ring-roller.

8. In a machine of the class described, the combination with a machine-frame; a rotary cylinder stationarily mounted in said frame, and means for operating same, of a flexible bolster horizontally stretched underneath said cylinder; a movable carriage on which said bolster is stretched; means for operating said carriage back and forth; a ring-roller composed of a plurality of rings resting against the under side of said bolster; a roller made of resilient material and upon which said ring-roller rests; adjustable bearings for said roller so as to raise or lower said sectional ring-roller; two plates suitably supported in said machine-frame and on each side of said sectional ring-roller; two retaining-plates suitably secured on the upper side of said first-mentioned plates and on each side of said sectional ring-roller, and rollers suitably journaled in said machine-frame to form supports at certain times for said bolster.

9. In a machine of the class described, the

combination with a machine-frame; a rotary cylinder stationarily mounted in said frame, and means for operating same, of a flexible bolster horizontally stretched underneath said cylinder; a movable carriage on which said bolster is stretched, the said carriage having sliding bearing on said machine-frame; a ring-roller composed of a plurality of rings resting against the under side of said bolster; a rubber roller upon which said ring-roller rests; a shaft for the rubber roller having bearings in said machine-frame; pinions secured on the ends of said rubber-roller shaft; racks secured to said carriage; the main shaft of the machine journaled in said machine-frame; drive-wheels keyed to said shaft and meshing with said racks and said rubber-roller pinions; means for operating said drive-shaft, and means for reversing same so as to move said carriage back and forth.

10. In a machine of the class described, the combination with a machine-frame; a rotary cylinder stationarily mounted therein, means for operating same, and watering means located over said cylinder, of a flexible bolster horizontally stretched underneath said cylinder; means for moving same back and forth; a ring-roller composed of a plurality of rings resting against the under side of said bolster, and a rubber roller upon which said ring-roller rests.

11. In a machine of the class described, the combination with a horizontally-held flexible bolster; a carriage on which same is stretched, and means for operating said carriage back and forth, of a ring-roller composed of a plurality of rings resting against the under side of said bolster, and a rubber roller upon which said ring-roller rests.

12. In a machine of the class described, the combination with a horizontally-held flexible bolster; a carriage on which same is stretched, and means for operating said carriage back and forth, of a ring-roller composed of a plurality of rings resting against the under side of said bolster, a rubber roller upon which said ring-roller rests, and adjustable bearings for said rubber roller so as to raise or lower said ring-roller.

13. A carriage for hide-working machinery, comprising a suitable frame; toothed racks suitably secured down each side of same; a bolster fixedly attached at one end to one end of said carriage, and adjustably attached at its other end to the other end of said carriage, and means for regulating the tension of said bolster from its adjustably-attached end.

14. A carriage for hide-working machinery, comprising a suitable frame; toothed racks suitably secured down each side of same, and bearing-grooves formed in the sides of said frame; a bolster fixedly attached at one end to one end of said carriage, and adjustably attached at its other end to the other end of

said carriage, and means for regulating the tension of said bolster from its adjustably-attached end.

15. A carriage for hide-working machinery, comprising a suitable frame; toothed racks suitably secured down each side of same; a bolster fixedly attached at one end to one end of said carriage, and adjustably attached at its other end to the other end of said carriage; means for regulating the tension of said bolster from its adjustably-attached end, and clamping means attached to the said bolster.

16. In a machine of the class described, the combination with a machine-frame; a rotary cylinder stationarily mounted in said frame; and means for operating same, of a flexible bolster horizontally stretched underneath said cylinder; a movable carriage on which said bolster is stretched; means for operating said carriage back and forth; a ring-roller, resting against the under side of said bolster, composed of a plurality of rings provided with central holes; a spindle passing through the central holes in said rings; means for preventing longitudinal movement of said rings, the said rings being capable of movement at right angles to said spindle by reason of said central holes, and a rubber roller upon which said ring-roller rests.

17. In a machine of the class described, the combination with a stationarily-mounted rotary cylinder, and means for operating same, of a flexible bolster horizontally stretched underneath said cylinder; means for moving same back and forth, and a roller underneath said cylinder and parallel thereto, constructed of a plurality of sections having independent movement of each other and in conformity with the thickness of the work under manufacture, so that all parts of the work under manufacture may be constantly kept in contact with the cylinder.

18. In a machine of the class described, the combination with a stationarily-mounted rotary cylinder, and means for operating same, of a flexible bolster horizontally stretched underneath said cylinder; means for moving same back and forth; a roller, underneath said cylinder and parallel thereto, constructed of a plurality of sections having independent movement of each other and in conformity with the thickness of the work under manufacture, so that all parts of the work under manufacture may be constantly kept in contact with the cylinder, and a roller made of resilient material and upon which the sections of said roller rest.

In testimony whereof I have signed my name to this specification in the presence of two subscribing witnesses.

JAMES WILLIAM DECKERT.
